F. A. BRAGG

RAILROAD TIE

Filed June 21, 1923

INVENTOR.
Frederick A. Bragg.
BY
Harry W. Bowen.
ATTORNEY.

UNITED STATES PATENT OFFICE.

FREDERICK A. BRAGG, OF SPRINGFIELD, MASSACHUSETTS.

RAILROAD TIE.

Application filed June 21, 1923. Serial No. 646,974.

To all whom it may concern:

Be it known that I, FREDERICK A. BRAGG, a citizen of the United States of America, residing at Springfield, county of Hampden, 5 Commonwealth of Massachusetts, have invented certain new and useful Improvements in Railroad Ties, of which the following is a specification.

This invention relates to improvements in 10 the construction of railroad ties of the type in which boxes or receptacles of suitable size are provided for supporting the rails of the main track. These boxes are connected together by pieces of abandoned railroad rail irons which serve as the connecting rods between the boxes.

An object of the invention is to simplify 20 and lessen the cost of construction of the usual wooden railroad tie, and at the same time materially increase the durability of its lasting qualities.

It is well known that material for railroad ties is becoming very scarce particularly the usual and well known chestnut tie 25 which has been in use for many years.

It is also well known that the rails after being in use for a certain length of time become worn so that they have to be discarded. It is proposed to use these abandoned rails 30 in constructing the present tie.

One of the objects of the invention is to make the tie elastic as well as durable. It is also proposed to thoroughly insulate the main rails for providing for the usual block 35 system which carries the current through the rails for operating the signals of the blocks.

Broadly, my invention comprises two boxes or receptacles which are filled with 40 concrete in which rest and are embedded the cross rail or tie piece which connects the boxes. Also embedded in these boxes are blocks of wood into which spikes which retain the main rails in place are driven.

45 These embedded rails on which the main rails rest are provided with insulating caps, or pieces, for insulating the main rails from the cross rails or tie rods.

Referring to the drawings:

50 Fig. 1 is a plan view of a section of one

form of my invention showing two of the completed ties and a portion of the main rail supported on the boxes;

Fig. 2 is a plan view of another form of a completed section showing a slight modification in which two cross ties, or rods, are employed in place of the single one shown in Fig. 1;

Fig. 3 is a detail sectional view on the line 3-3 of Fig. 1, showing the interior 60 construction of one of the supporting boxes or receptacles that receives the cross tie and the wooden blocks imbedded in the concrete;

Fig. 4 is a detail perspective view, similar to Fig. 3, but showing the completed box or 65 receptacle and illustrating the upper surface on which the main rail is placed;

Fig. 5 is a detail sectional view on the line 5-5 of Fig. 2 showing the two cross or connecting tie rails located within the 70 box and a portion of the main rail supported thereon; and

Fig. 6 is a detail view of one of the rail supporting boxes.

Referring to the drawings in detail:

1 designates the main rails and 2 the cross or tie rails. 3 designates one of the boxes which may be formed of sheet metal and made of a suitable size as to length, breadth and height. In practice they would be substantially one cubic foot. The opposite sides of the box 3 are cut open a portion of their height and the cut out portion of the metal is bent downward as shown in Figs. 3 and 6 at 4. Resting on the bent over or 80 turned in portions 4 of the boxes are the cross rails or tie pieces 5. The lower flange 6 of the rail is shown as engaging the pieces 4. The distance of the pieces 4 from the top of the box is substantially equal to the 85 height of the rail 5, so that its upper surface 5' is flush with the upper edges of the box as shown in Figs. 3, 4, and 5. 7 indicates blocks of wood, the lower surfaces of which engage the oppositely located flanges 6 of the rail and extend upward flush with the upper surface 5' of the rail 5. Each of the blocks 7 is incased in a metal casing 7' solidly packed with concrete material 8 which completely fills the box and all of 100

the space surrounding the rail 5 and the casting 7' which receives the block 7. The main rails are then placed on the top of the boxes as shown in Fig. 1 and secured in place by driving the usual spikes 9 into the blocks 7, whereby the main rails 1 are firmly secured in place similar to the usual way of nailing the main rail to the usual wooden tie.

Referring to Figs. 2 and 5 the single cross rail or tie rod shown in Fig. 1 is replaced by two pieces of cross rails or tie rods indicated at 10 and 11. These rails, as shown in Fig. 5, are placed side by side with their flanges 12 in contact with each other and located on the oppositely located bent over plates 4 of the boxes 3. They are tied together laterally by means of the rods 13 and the nut construction 14. These rods 13 serve the double purpose of holding the rails 10 and 11 in fixed relation to each other and also to prevent the rails from moving longitudinally in the boxes 3. 15, 16 and 17 are blocks of wood placed on the flanges 12 and located outside of and between the rails 10 and 11 as shown in Fig. 5. These blocks are incased in the metal casings 17'. The blocks serve to secure the main rails 1 to the boxes 3. For the purpose of insulating the tie rails 5, 10 and 11 from the main rail 1 caps 18 of insulating material are placed on the tie rails and directly under the flange 1' of the main rails. The cross rails 10 and 11 are of smaller construction or cross sectional area than the single cross rail shown in Figs. 1 at 2.

It will be seen from this description that I have produced a railroad tie which possesses lasting qualities and which makes use of discarded pieces of railroad iron or rails which serve as the connecting ties or rod portion of the completed ties. The construction also possesses elastic qualities and one that may be readily installed or replaced.

What I claim is:

45 1. A combination of main track rails and oppositely located receptacles for supporting the main track rails, tie rods connecting the receptacles, a suitable hardening material poured into the receptacles, for securing the tie rods in place and means for attaching the main rails to the receptacles.

50 2. A railroad tie construction comprising, in combination, a pair of boxes having ledges or flanges located therein, a piece of railroad iron having its lower flange supported on said ledges or flanges, the boxes being filled with a hardening material for permanently securing the iron in place in the boxes, and means in the boxes for securing the main rails of the track thereto.

60 3. A railroad tie construction comprising in combination, a pair of oppositely located boxes or receptacles having supporting portions therein, a piece of railroad iron having

its lower flange supported on said portions, 65 said iron serving as a connecting rod for the boxes, blocks in the receptacles and a hardening filling material filling the space in the boxes and serving to retain the blocks and tie rods in place, the blocks and tie rods 70 serving to support the main rails and for attaching the same to the boxes or receptacles.

4. A combination of track rails and oppositely located receptacles, connecting tie rods in said receptacles for connecting the same 75 together, securing blocks in the receptacles for attaching main rails to the boxes, the interior of the boxes being filled with concrete material to provide a permanent construction, and means for insulating the tie 80 rods from the main track rails.

5. A combination of track rails and a pair of oppositely disposed boxes, or receptacles, connected by two tie rods of railroad irons, a bolt for connecting the rods together, each 85 of the boxes being filled with concrete for permanently securing the railroad irons in place in the receptacle, main track rails secured to the boxes by means of the embedded material possessing suitable elastic qualities 90 for receiving rail securing spikes, as described, and for producing the necessary elasticity for the main track rails.

6. A combination of track rails and a pair of main rail support-boxes, a shelf part on 95 each box, a piece of railroad iron having its flange supported on said part for connecting the boxes together, casings in the boxes, blocks of wood in the casings for attaching main rails thereto, the boxes being filled with 100 concrete material for securing the casings and cross tie rail iron in place.

7. A supporting box for a railroad main line rail comprising a member having oppositely located openings, a supporting ledge 105 part adjacent each of the openings to receive a member for connecting two boxes together to form a tie, a connecting member, said box being designed to receive concrete material for securing the connecting member for the 110 boxes together.

8. A combination of track rails and oppositely located rail supporting receptacles, said receptacles having oppositely located openings, a tie member in the openings for 115 connecting the receptacles together, cement for securing the tie member in the rail supporting receptacles, blocks in the cement for attaching the main line track rails to the said supporting receptacles.

9. A combination of track rails and oppositely located receptacles, said receptacles having oppositely located openings, a tie rod member in the openings for connecting the receptacles together, cement for securing the tie rod member in the receptacles, blocks in the cement for attaching the track rails to the said supporting receptacles, and insulat-

ing material located between the tie rod members and the main line rails.

10. A combination of track rails and a pair of rail supporting members, railroad iron connecting said members together, the tread part of the connecting railroad irons serving to receive the flanges of the track rails, blocks of wood

in the rail supporting members into which nails for securing the track rails to the connecting members are driven, cement in the members to secure the blocks and the connecting railroad iron in place in the said supporting members.

FREDERICK A. BRAGG.
